WINDING FOR ELECTRICAL APPARATUS

Andrew Glassanos, Pittsfield, Mass., assignor to General Electric Company, a corporation of New York

Application October 24, 1957, Serial No. 692,223

8 Claims. (Cl. 336—192)

This invention relates to electrical apparatus, and more in particular to an improved winding construction for stationary electrical induction apparatus such as transformers, reactors, and the like.

The low voltage winding leads of high current electrical induction apparatus, such as transformers adapted to supply electrical furnaces, are frequently comprised of a plurality of parallel conducting bars instead of only one large bar connected to each end of the winding, due to the difficulties involved in connecting and supporting a bar of the dimensions required to carry the full winding current. Since the reactance of the leads is proportional to the spacing between leads connected to opposite ends of the winding, the leads extending from opposite winding ends are preferably alternated rather than grouped in order that the reactance may be minimized by having the effective spacing of the leads as low as possible. That is, the bars generally extend from the winding in a common plane, with each bar connected to one end of the winding being positioned between bars connected to the other end of the winding.

This lead arrangement ordinarily presents no problems in conventional types of furnace transformer windings (e. g. where the low voltage winding is comprised of a plurality of parallel connected winding sections). Occasionally, however, it is desirable that the low voltage winding comprise a single turn of a sheet of conducting material, with the leads extending from opposite sides of an axially extending gap separating the edges of the sheet which define the ends of the single turn. This type of winding may be generally described as a "sheath" winding. In the past, when such single turn windings were employed, attempts to alternate the bar leads to reduce reactance resulted in complicated and uneconomical bar lead structures, since all of the bars connected to each end of the winding were connected to the winding at one peripheral location.

It is therefore an object of this invention to provide an improved sheath winding for electrical apparatus.

It is also an object to provide a bar lead arrangement for single turn electrical apparatus windings wherein alternation of leads connected to opposite sides of the winding to reduce lead reactance does not result in complicated or uneconomical bar lead structures.

A further object of this invention is to provide a single turn electrical winding comprised of a sheet of conducting material, wherein the gap separating the edges of the sheet which define the ends of the single turn is staggered in order that bar leads connected to opposite sides of the winding may be alternated without the necessity for complicated or uneconomical bar lead structures.

Briefly stated, and in accordance with the preferred aspects of my invention, I provide a winding for an electrical apparatus, such as furnace transformers, the winding comprising a hollow cylindrical conducting member. A gap extends through the member axially from one end to the other thereof, and the ends of the gap are preferably circumferentially displaced. A plurality

of radially extending flanges are provided on the cylindrical conducting member on each side of the gap, the flanges being adapted to be connected to bar leads. The gap separating the ends of the winding is preferably stepped, that is, the gap has a plurality of portions extending axially on the cylindrical member joined by at least one circumferentially extending portion.

While the specification concludes with claims particularly pointing out and distinctly claiming the subject matter which I regard as my invention, it is believed that the invention will be better understood from the following description taken in connection with the accompanying drawing.

In the drawing:

15 Fig. 1 is a perspective view of a sheath winding according to one aspect of my invention, and illustrating the winding disposed about the leg of a magnetic core,

Fig. 2 is a side view of the winding of Fig. 1, and illustrating a plurality of bar leads extending from the 20 winding,

Fig. 3 is a cross-sectional view of the winding of Fig. 2 taken along the lines 3—3,

Fig. 4 is a cross-sectional view of an alternate means of providing flanges on the winding of Figs. 1 and 2, and

25 Fig. 5 is a side view of a modification of the winding of Fig. 2.

Referring now to the drawing, and more in particular to Fig. 1, therein is illustrated a hollow cylindrical conducting member 10 formed of a sheet of conducting material, and comprising a single turn winding. The winding leg 11 of a magnetic core extends axially through the member 10, and additional windings (not shown for the sake of clarity) may also be provided surrounding the core 11.

35 A gap 12 is provided extending axially through the conducting member 10, and the axial ends of the gap 12 are circumferentially displaced about the member 10. For example, as illustrated in Figs. 1 and 2, the gap 12 may comprise a plurality of axially extending portions

40 13 joined by circumferentially extending portions 14. Radially outwardly extending flanges are provided extending from each side of the axially extending portions 13 of the gap 12. As illustrated in Fig. 3, the flanges 15 preferably lie in parallel planes to facilitate attachment of leads thereto. The flanges 15 may be formed 45 from the same sheet of material as the cylindrical member 10, as illustrated in Figs. 1 and 3, or they may be separate angle shaped members welded or otherwise suitably affixed to the member 10 as illustrated in Fig. 4.

50 A plurality of axially extending bars 20 of conducting material (Figs. 2 and 3) are connected to the flanges 15 on one side of the gap 12, with one bar 20 being connected to each flange, and a plurality of axially extending conducting bars 21 are connected to the flanges

55 15 on the other side of the gap 12 with one bar 21 being connected to each flange. As illustrated in the drawing, the bars extend in one direction from the flange to which they are connected, and the bars 20 and 21 are connected to the sides of the flanges 15 away from the gap 12.

60 The axially extending portions 13 of the gap are spaced circumferentially so that each of the bar leads extending from a flange on one side of the gap is located between bars extending from the opposite side of the gap, and the circumferential distance between all of the bars is substantially the same.

65 If desired, one or more pairs of bar leads may be connected to more than one winding flange. Thus, as illustrated in Fig. 5, the ends 30 of the gap 12 are in the same peripheral location and a central portion 31 of the gap is circumferentially displaced from the end portions. The bar leads 32 and 33 joining the uppermost winding flanges extend downwardly and also join

the lowermost winding flanges. The remaining bars 34 and 35 join the central flanges. In this arrangement the sum of the axial lengths of the endmost flanges should equal the axial length of the central flange in order that the bar leads carry equal currents. Additional steps, which may be connected to additional bars, may also be provided in this arrangement, if so desired, without departing from the spirit or scope of my invention.

From the preceding disclosure it is seen that the present invention, by circumferentially displacing portions of a gap extending through the winding, has provided means whereby the leads extending from the winding may be alternated to minimize lead reactance without the necessity for complicated lead configurations.

It will be understood, of course, that, while the forms of the invention herein shown and described constitute preferred embodiments of my invention, it is not intended herein to illustrate all of the possible equivalent forms or ramifications thereof. It will also be understood that the words employed are words of description rather than a limitation, and that various changes may be made without departing from the spirit or scope of the invention herein disclosed, and it is aimed in the appended claims to cover all such changes as fall within the true spirit and scope of the invention.

What I claim as new and desire to secure by Letters Patent of the United States is:

1. An electrical winding comprising a hollow cylindrical conducting member, a stepped gap extending axially through the wall of said cylindrical member, radially extending flanges on said member adjacent axially extending portions of said gap, and parallel leads connected to said flanges.

2. An electrical winding comprising a hollow cylindrical conducting member, a gap extending through the wall of said cylindrical member, said gap having a plurality of portions extending axially of said member and joined by at least one circumferentially extending portion, a plurality of radially outwardly extending flanges on said member on each side of the axial portions of said gap, and parallel leads connected to said flanges.

3. A winding for electrical apparatus comprising a hollow cylindrical conducting member, a gap extending axially through said member from one end to the other end thereof, the ends of said gap being circumferentially displaced, and a plurality of radially extending flanges on said member on each side of said gap, and coplanar parallel leads connected to said flanges, with alternate leads being connected to opposite sides of said gap.

4. A winding for electrical apparatus comprising a

50
4
hollow cylindrical conducting member, a gap extending axially through said member from one end to the other end thereof, the ends of said gap being circumferentially displaced, and a plurality of flanges extending radially outwardly from said member on each side of said gap, said flanges being circumferentially displaced, and coplanar parallel leads connected to said flanges, alternate leads being connected to opposite sides of said gap.

5. A winding for a transformer comprising a hollow cylindrical conducting member, a gap extending through said member from one end to the other end, the ends of said gap being circumferentially displaced, a plurality of flanges extending radially from said member on each side of said gap, and a conducting lead connected to each of said flanges and extending axially of said winding, said flanges being circumferentially displaced so that alternate leads are connected to flanges on opposite sides of said gap.

6. The winding of claim 5 in which the gap has portions extending axially of said member and portions extending circumferentially of said winding joining the axially extending portions, and the flanges extend from said member adjacent the axially extending portions of said gap.

25
7. A stationary electrical induction apparatus comprising a magnetic core having a winding leg, and a winding surrounding said leg and insulated therefrom, said winding comprising a hollow cylindrical conducting member having a gap extending between the ends thereof, the ends of said gap being circumferentially displaced, and a plurality of flanges extending radially from said member adjacent each side of said gap.

35
8. A stationary electrical induction apparatus comprising a magnetic core having a winding leg, and a winding surrounding said leg and insulated therefrom, said winding comprising a hollow cylindrical conducting member having a gap extending from one end to the other end thereof, the ends of said gap being circumferentially displaced, a plurality of flanges extending radially from 40 said member on each side of said gap, and a bar lead extending axially of said winding from each flange, the flanges being circumferentially displaced so that alternate bar leads are connected to flanges on opposite sides of said gap.
